(57) **CLAIM**

The ornamental design for a prosthetic foot component, as shown and described.

DESCRIPTION

FIG. 1 is a perspective view showing a prosthetic foot component showing my new design;

FIG. 2 is a first side elevational view of the prosthetic foot component in FIG. 1;

FIG. 3 is a second side elevational view of the prosthetic foot component in FIG. 1;

FIG. 4 is a front elevational view of the prosthetic foot component in FIG. 1;

FIG. 5 is a rear elevational view of the prosthetic foot component in FIG. 1;

FIG. 6 is a top plan view of the prosthetic foot component in FIG. 1; and,

FIG. 7 is a bottom plan view of the prosthetic foot component in FIG. 1.

The broken lines are included for the purpose of illustrating environmental structure and form no part of the claimed design.
